DESIGN FOR A HOUSING FOR DISPENSING APPARATUS

Hosmer L. Blum, Fort Wayne, Ind.

Application November 25, 1938, Serial No. 81,362

Term of patent 7 years

To all whom it may concern:

Be it known that I, Hosmer L. Blum, a citizen of the United States, residing at Fort Wayne, Allen County, Indiana, have invented a new, original, and ornamental Design for a Housing for Dispensing Apparatus, of which the following is a specification, reference being had to the accompanying drawing forming a part thereof.

Figure 1 is a front elevation of the design for housing for dispensing apparatus.

Figure 2 is a left side elevation of Figure 1.

Figure 3 is a right side elevation of Figure 1.

Figure 4 is a plan view of the design for housing for dispensing apparatus.

The rear elevation of the housing is substantially the same as Figure 1.

I claim:

The ornamental design for a housing for dispensing apparatus, as shown and described.

HOSMER L. BLUM.
